UNITED STATES PATENT OFFICE.

JOHN MANSFIELD DEAN AND ANDREW N. KITTRELLE, OF MEMPHIS, TENNESSEE.

RESPIRATORY MASK.

Application filed May 1, 1923. Serial No. 636,003.

To all whom it may concern:

Be it known that we, JOHN MANSFIELD DEAN and ANDREW N. KITTRELLE, citizens of the United States, residing at Memphis, in the county of Shelby and State of Tennessee, have invented certain new and useful Improvements in Respiratory Masks, of which the following is a specification.

This invention relates to respiratory masks and more particularly to masks for surgeons' and dentists' use during operations upon the mouth, throat, nose or eyes.

The particular object of this device is to provide a mask having means whereby mild antiseptics may be retained therein in such a position that the air drawn in by the wearer will pass therethrough before being inhaled.

A further object is to provide an anti-septic carrying mask in which a provision is made for the insertion and removal of sterilized gauze or other absorbent material, impregnated with a mild, pleasant smelling antiseptic substance, between the nostrils of the wearer and the inlet apertures.

A still further object is to provide a mask which will comfortably conform to the outline of the face of the operator, covering as little space as possible, will not obstruct the view, easily kept clean, light of weight, strong, durable, and inexpensive to manufacture.

It is well known that operations upon the mouth, throat, nose or eyes bring the face of the operator and patient in comparatively close relation and where the patient is suffering from an infection of the oral or nasal cavity, the operator is in danger of contracting the disease unless proper precautions are taken to intercept the passage of any germs which may be expelled by the patient, and it is the object of this device to safeguard the operator from such dangers.

Further where no diseased condition exists, halitosis may be present in either the patient or operator, and by using a device of the present type this condition would not be noticeable and consequent unpleasantness to either party prevented.

A more thorough and intelligent understanding of the device may be had upon referring to the following drawing, in which:

Figure 1 shows a view of the device applied.

Fig. 2 is a rear view of the mask, and Fig. 3 is a vertical transverse section thereof.

Like numerals of reference refer to like parts throughout the several views of the drawings.

The respirator consists of an upper nose enclosing portion 1, of inverted, substantially V-shaped contour and a lower mouth covering portion 2 of circular shield like form. The portion 1 is preferably of soft rubber and shaped to conform to the general contour of the nose while the lower portion 2 is constructed of some light weight material, preferably celluloid; that also being shaped to snugly fit the features below and on either side of the mouth. These portions are cemented together at their contacting surfaces.

The portion 2, is of substantially circular contour and dished or concave having the side wings 3, which are adapted to lie against the cheeks, and the lower edge cut out as shown at 4, to accommodate the chin.

The upper edge of the portion 2, has formed integral therewith the offset portion 5, extending forwardly at right angles therefrom and having its upper and lower side provided with apertures 6 which open into the chamber 7, which in turn opens into the interior of the mask. Sterilized gauze or cotton 8, impregnated with a suitable mild antiseptic oil such as eucalyptus, is to be placed in this chamber.

The portion 1, which covers the nose, is provided at its under side 9, with a thickened portion 10 which fits snugly beneath and is cemented to the offset portion 5 of the lower portion 2, and is provided with passages 11 which align with the lower passages 6, for establishing communication with the atmosphere.

Fixed to the side edges of the portion 2, at suitable points are loop members 12 to which are hingedly attached hooked retaining members 13 for retaining the mask in position. It may be seen that by using the hooked members instead of a head band as is customary, the mask may be put on and removed quickly and with little trouble.

Having described the device, in accordance with the drawing, it is to be understood that various changes and modifications may be made in the same without departing from the spirit of the invention as claimed.

What is claimed is:

1. In a respirator, a unitary structure comprising an upper nose enclosing elastic portion having a plurality of apertures at the lower end thereof, and a lower mouth covering resilient portion, means to provide a forwardly extending semicircular antiseptic chamber projecting into and resting upon the lower end of and enclosed by said nose enclosing portion, said chamber opening into the mouth covering portion for the insertion of antiseptic carrying material, and having a plurality of apertures through the upper and lower sides thereof, the lower apertures aligning with the apertures in the nose enclosing portion and the other apertures opening upwardly through the nose enclosing portion, and means hingedly attached to said resilient portion for retaining the same in position when in use.
2. In a respirator, a unitary structure comprising an inverted substantially V-shaped nose fitting and enclosing portion of soft flexible material, open at its rear end and provided at its front end with an apertured lower front wall, a mouth enclosing portion of resilient material and of circular shield like form, adapted to snugly engage over the lower portion of the face, and depending from and having its upper part provided with means extending upon the front wall of the nose enclosing portion to provide an antiseptic chamber, said chamber having a plurality of apertures through its upper and lower sides, the apertures in the lower side aligning with the apertures in the nose enclosing portion, and the apertures in the upper side opening into the nose enclosing portion, and means attached to the side of said portion of resilient material for retaining the structure in position when in use, said nose enclosing portion being of materially less width than the said mouth enclosing portion and located at the upper portion and upon the longitudinal center thereof.

In testimony whereof, we affix our signatures hereto:

JOHN MANSFIELD DEAN.
ANDREW N. KITTRELL.
